Application December 30, 1936, Serial No. 118,285

36 Claims. (Cl. 62—119.5)

This invention relates to continuous absorption refrigeration apparatus, and more particularly to means for circulating fluids therein. This application is a continuation in part of our application for Letters Patent Serial No. 97,942, filed Aug. 26, 1936.

Absorption refrigeration systems of the three fluid type include a refrigerant generator, an evaporator, and an absorber as principal elements. An inert gas or pressure equalizing medium is circulated through conduits interconnecting the absorber and the evaporator, while an absorption liquid for the refrigerant is circulated through conduits interconnecting the absorber and the generator. The volume of pressure equalizing medium circulated between the absorber and evaporator is much greater than the volume of absorption solution circulated between the absorber and the generator. It is essential that the apparatus be provided with some means for assuring the proper circulation of the absorption medium in its circuit and of the pressure equalizing medium in its circuit. Heretofore, it has been common practice to employ separate and independent means for circulating each of these mediums.

According to the present invention, it is proposed to circulate both mediums by a common source of energy without sacrificing the advantages of prior known modes of circulating these mediums and at the same time avoiding the many disadvantages. More specifically, this invention proposes to create a pressure differential in the inert gas circuit for the purpose of circulating the gas therein at a desired rate, and to employ this pressure differential to circulate the absorption medium in its circuit at a desired rate which is much less than but substantially proportional to the rate of inert gas circulation.

A preferred manner of practicing the invention is to bleed off a relatively small portion of gas from a high pressure area in the inert gas circuit and to bubble this gas into a column of absorption liquid. The mixture of liquid and gas results in the lowering of the specific gravity of this column and the raising of the surface level of the liquid to an elevated point.

Heretofore, it has been common practice to employ a vapor lift pump for circulating the absorption solution. This pump is operated by bubbles of refrigerant vapor produced in the boiler. Such pumps have many disadvantages and limitations which greatly restrict their use. For example, the small diameter vapor lift pump must be located in a high temperature region in

which it is subject to corrosion and clogging. The refrigerant vapor must be maintained at a high temperature to prevent its condensation and absorption by the absorption liquid. The rate of circulation varies over a wide range as it is a function of the boiler temperature, and is accordingly difficult to control.

The present invention, however, entirely avoids the many disadvantages and undesirable characteristics of the vapor lift pump, utilizes the great simplicity of the gas lift type of pump, and provides a construction which functions equally well in either a high or low temperature zone. This is for the reason that our pump is operated by inert gas which does not condense and is not absorbed by the absorption liquid. The introduction of the inert gas into the absorption liquid is not dependent upon the temperature of either the gas or the absorption liquid, and the rate of circulation through the pump is substantially unaffected by wide variations in the temperature of the gas supplied thereto. It is therefore possible to locate the pump in any part of the solution circuit and to circulate the solution at will independently of the temperature of the boiler.

By reason of our novel arrangement of the inert gas and the absorption solution circuits, it is possible to circulate both the inert gas and the absorption liquid at the proper respective rates for optimum operating conditions without resorting to the use of valves or other restricting devices. And this is accomplished by the simple expedient of diverting only a very small percentage of the main inert gas stream from its normal circuit between the evaporator and absorber. In addition to the many advantages provided by our arrangement, as hereinabove pointed out, we have found that it also provides an unusually facile method of governing and maintaining stable operating conditions within the system.

A second embodiment of the invention shows the solution pump as being located in the enriched solution return conduit extending between the lower end of the absorber and the boiler assembly. This arrangement permits the entire absorber to be located between the upper and lower limits of the boiler assembly rather than above the boiler. An unusually compact boiler-absorber assembly is therefore possible, and this desirable arrangement is achieved without sacrificing simplicity or efficiency.

It is accordingly the object of the invention to provide a novel absorption refrigeration system

having the advantages and characteristics pointed out by way of illustration hereinabove. Still other advantages will become apparent from the description taken in connection with the drawing wherein:

Figure 1 is a diagrammatic view in elevation of one form of the invention showing a part of the apparatus broken way: and,

Figure 2 is a diagrammatic view in elevation showing a modified embodiment of the invention.

Referring to the drawing in detail, and first to Figure 1, a continuous absorption refrigeration apparatus is shown consisting of a boiler-analyzer assembly B, a rectifier R, an absorber assembly A¹, A², a condenser C, an evaporator E, a gas pump F, and two liquid gas lift pumps P¹ and P², as essential elements, these elements being connected to form the complete refrigeration apparatus by various conduits some of which are in heat exchange relation.

The boiler-analyzer assembly B may be constructed with a main horizontal body portion or boiler 10, and an upstanding portion or analyzer 11 located near one end of the boiler. A conduit 12 extends from the top of the analyzer 11 through rectifier R and then into the top of the condenser C and serves to convey refrigerant vapor from the boiler to the condenser. Both the rectifier and the condenser may be cooled in any suitable manner, as by the usual heat radiating fins. The discharge end 13 of the condenser extends into the top of the evaporator E.

The absorber assembly consists of two adjacent and downwardly inclined vessels A¹, A². This assembly is located below the evaporator E and is connected thereto by means of conduits 14 and 15. Conduit 14 leading into the lower end of absorber A¹ and conduit 15 leading into the lower end of absorber A². The top portions of the two absorbers are connected by conduit 16 terminating in a conduit 17 leading into the intake of the fan chamber 18 of gas pump F. An electric motor 19 may be hermetically sealed within the system and connected to drive a fan or impeller within chamber 18. A conduit 20 serves to conduct the gas discharged by gas pump F into evaporator E, while conduit 14 serves to conduct the refrigerant laden inert gas out of evaporator E. Gas conduits 14 and 20 are preferably in heat exchange relation at 21.

The absorbers A¹ and A² may be of any suitable form, and may contain baffles such as shown at 22 to retard the passage of liquid therethrough so as to increase the surface contact between the absorption fluid and the refrigerant laden inert gas. It is important that the absorbers be cooled in some manner. This may be done by means of air-cooled, heat dissipating fins 23 affixed to the exterior surfaces of the absorbers.

The absorption fluid circuit consists of conduit 24 leading from the bottom of the boiler 10 into the bottom portion of a U tube 25. The two legs 26 and 27 of this U tube are connected to the top portion of absorbers A¹ and A² respectively. U tube 25 constitutes a part of the gas lift pumps P¹ and P², as will appear more fully hereinbelow. Conduits 28 and 29 lead from the lower ends of the absorbers into a reservoir 30. A conduit 31 conveys enriched absorption solution from reservoir 30 into an upper portion of the analyzing column 11. Conduits 31 and 24 are in heat exchange at 32.

We have discovered that a miniature fan op-

erating at relatively low speeds is capable of producing a pressure differential equivalent to several inches of water when operating in a gaseous medium having a relatively high molecular weight, as for example nitrogen, when under a pressure equivalent to that used in a refrigerating system employing a pressure equalizing medium. If an inert gas of low molecular weight like hydrogen is used, it is necessary to employ a fan many times larger than is the case with a dense gas. The larger fan, of course, requires a larger motor and consumes more power than the miniature fan and motor used in our construction. The significance of the foregoing will be apparent when it is realized that for the same amount of useful work, a tremendous saving in operating and construction cost may be made by employing a dense, inert gas rather than a light gas.

The unique advantage of generating a relatively high pressure differential in a refrigerating apparatus employing a pressure equalizing medium is that the pressure may be used to operate a liquid gas lift pump as well as to circulate the inert gas. Moreover since the volume of absorbent solution circulated is small compared to that of the pressure equalizing medium, a small portion of the inert gas discharged from the gas pump F may be used to operate the liquid gas lift pumps P¹ and P² for circulating the absorbent solution without increasing the power required to operate the gas pump F by more than an insignificant amount.

The gas pump F can be controlled in any desired manner such as manually or automatically in accordance with temperature conditions, for instance, in some part of the system.

The apparatus of Figure 1 operates in the following manner:

The apparatus may be charged in accordance with known practices with any suitable fluids such as ammonia as the refrigerant, water as the absorbent, and any dense, inert gas, such as nitrogen, which serves as the pressure equalizing medium. The boiler contains a mixture of ammonia and water and may be heated in any suitable manner such as by an electric cartridge heater or by a fluid fuel burner. Vapor is liberated from the solution and passes upwardly through conduit 12, rectifier R, and into the top portion of condenser C. Any water vapor which remains in the refrigerant vapor after passing through the analyzing column 11 is condensed as it passes through the rectifier R and flows back into the analyzing column 11.

The ammonia vapor is condensed in the condenser C and flows downwardly into conduit 13, and from there into the top of the evaporator E. Flowing down through evaporator E, the liquid ammonia evaporates in the stream of inert gas flowing through the evaporator E thereby producing refrigeration.

When the gas pump F is energized gas will be circulated between the evaporator E and absorbers A¹ and A², thus delivering the ammonia laden inert gas from the former to the latter where the ammonia gas is absorbed by the absorption medium. The gas discharged from the top of the absorbers is comparatively pure inert gas and is led back to the bottom of the evaporator after passing through the gas pump F and heat exchanger 21.

A small part of the inert gas discharged from gas pump F is bled off by conduit 32. This gas divides in the inverted U tube 33 and flows in

substantially equal portions to legs 26 and 27 of U tube 25. P¹ and P² together constitute what we prefer to call a twin gas lift pump as will become more apparent hereinbelow. The connections between U tubes 25 and 33 are positioned somewhat below the normal level of absorption fluid in the system and thus two liquid gas lift pumps P¹ and P² are formed. However, one pump does not function entirely independently of the other due to conduit 25 which interconnects the lower end of the pumps.

Assuming that fan F is started after a period of rest, the twin gas lift pump operates as follows: At first the absorption solution liquid level will be at rest in legs 26 and 27 and in U-tube 33. As soon as fan F begins to build up the inert gas pressure in conduit 32 and U-tube 33, the liquid level will be depressed until such time as the liquid therein is forced into legs 26 and 27. It is our observation that the gas does not pass simultaneously into each of the legs 26 and 27, but on the contrary a bubble of gas passes into one leg and immediately upsets the equilibrium between the two legs so that the liquid level rises in the lighter of the two columns and falls in the heavier column. Eventually a gas bubble passes into the other leg and causes the liquid column in conduit 25 to move in the opposite direction. The gas then continues to bubble into first one leg and then the other and the liquid in conduit 25 continues to oscillate and in such manner as to govern automatically the distribution of gas between the two legs in equal amounts if the several pump conduits are of the same size, or in unequal amounts if the conduits are of different sizes. It therefore follows that the absorption solution discharges alternately from the tops of the two legs.

It will accordingly be obvious why we choose to term our pumping device a twin gas lift pump which can be utilized to divide a stream of liquid or to elevate liquid to a single chamber or to two separate chambers. The oscillating piston of liquid in conduit 25 seems to act as a governor tending to maintain the rate of flow constant both from the pump as a whole and from each of the respective legs.

It will therefore be understood that the gas delivered into legs 26 and 27 is under a higher pressure than the gas at the top of the absorbers into which the legs discharge, and that bubbles of gas and slugs of absorption fluid will alternately flow from the top of legs 26 and 27 into the top sections of the absorbers A¹ and A² respectively. From this point the absorption fluid flows downwardly over baffles 22 absorbing ammonia gas passing through the absorbers in counterflow to the absorption liquid. The enriched absorbent solution flows into receiving vessel 30 through conduits 28 and 29. Vessel 30 may be dispensed with if desired. From vessel 30 the relatively cool, rich fluid flows back to an upper portion of the analyzer column 11, after first passing in heat exchange relation at 34 with weak absorption fluid from boiler 10.

The enriched absorption fluid returned to the analyzer immediately comes into contact with a mixture of ammonia and water vapor. The rich absorption fluid having a lower boiling point temperature than the liquid from which the vapor bubbles were generated partially condenses the vapor. The heat of condensation is given up to the enriched fluid and vaporizes ammonia therefrom. That a great saving in heat is accomplished by this mode of operation is at once

apparent. Not only is a relatively small proportion of absorbent vapor left to be removed by rectifier R, but the heat which would otherwise be dissipated from the rectifier is utilized in the analyzing column to liberate additional refrigerant.

Referring now to Figure 2, it will be seen that the general arrangement is very similar to that shown in Figure 1 and comprises a boiler-analyzer assembly B, a condenser C, an evaporator E, an absorber A, a liquid gas lift pump P, and a gas pump F, as essential elements, these elements being connected by conduits to form a complete refrigeration apparatus.

15 The boiler-analyzer assembly B consists of a lower, horizontally extending portion or boiler 50 and a vertical analyzing column 51 located near one end of the boiler. A conduit 52 leads from the top of the analyzer through the rectifier R and into the top of condenser C. The condenser discharges into the top of evaporator E through conduit 53.

20 The absorber A is located below the evaporator and may be of any desired form, the one shown being similar to one of the absorbers shown in Figure 1. The absorber A is connected to the evaporator E by means of gas conduits 54, 55 and 56, conduits 54 and 56 preferably being in heat exchange relation at 57. A gas pump F comprising an electric motor 58, and a centrifugal fan 59, serves to connect conduits 54 and 55, it being noted that conduit 54 opens into the intake of the fan and conduit 55 connects with the discharge thereof.

25 The absorption fluid circuit consists of a conduit 60 leading from the bottom of the boiler 50 to the top of the absorber A; another conduit 61 connects the bottom of the absorber with a receiving vessel or reservoir 62. A U-shaped conduit 63 interconnects vessel 62 and an elevated gas separation vessel 64, as shown in Figure 2. Leading from vessel 64 is a conduit 65 which conducts the enriched aqua back to an upper portion of the analyzer 51 after first passing in heat exchange relation at 66 with weak aqua.

30 In order to circulate the absorption fluid in this circuit, it is necessary to elevate the liquid from receiving vessel 62 into the elevated vessel 64, it being observed that the level of the liquid in this portion of the system during normal operation is somewhere between the bottom and top of receiving vessel 62. According to this embodiment of the invention, liquid is elevated from vessel 62 into vessel 64 by bleeding off a portion of the inert gas from the discharge side of gas pump F and bubbling it into the left-hand leg of U tube 63 by means of a conduit 67. The connection of conduit 67 with U tube 63 should, of course, be somewhat lower than the liquid level existing in the left leg of U-shaped conduit 63. The liquid level in this leg will be higher than the level in vessel 62 due to the pressure differential existing across the gas pump F.

35 Since vessel 64 is vented through conduit 68 to some other part of the system, such as conduit 54, it is apparent that the gas pressure in conduit 67 is greater than that existing in vessel 64 when the refrigerating system is in operation. Consequently, alternate bubbles of inert gas and slugs of absorption fluid will form in the longer leg of U tube 63, thus causing the liquid to be elevated into vessel 64 in the same manner as described above in connection with gas lift pumps P¹ and P² shown in Figure 1.

In this embodiment it is necessary that the absorber be positioned below the top of the boiler-analyzer assembly rather than thereabove as in the first embodiment. This is for the reason that the absorption liquid flows by gravity from the boiler to the absorber. Accordingly, it will be manifest that this arrangement has the very great advantage of compactness—particularly in a vertical direction. This feature is especially important in the application of the invention to household refrigerators where the space limitations for the apparatus are very rigid.

It is thought unnecessary to go into a detailed description of the mode of operation of the modification just described since its operation will be apparent from the description just given, and particularly in view of the complete description given of Figure 1. Thus it will be apparent that refrigerant is generated in boiler 50 by the application of heat which refrigerant is condensed in condenser C and delivered in liquid form to the evaporator. The ammonia flowing through the evaporator E readily evaporates into the inert gas stream and is carried away through conduit 54. The larger portion of this gaseous mixture is delivered into the lower end of absorber A through which it passes in counterflow to and in intimate absorption relationship with weak absorbent medium from boiler 50. By the time the refrigerant inert gas mixture reaches the top of the absorber, most of the ammonia gas has been absorbed. Relatively, pure inert gas is then returned to the evaporator through conduit 56 after passing in heat exchange relation with the mixture of inert gas and ammonia flowing from evaporator E at 57.

A small portion of the gaseous mixture discharged from the gas pump F is led through conduit 67 and bubbled into the left leg of U tube 63 and elevates the enriched absorbent medium into vessel 64. The gas used in the liquid gas lift pump P, thus by-passes the absorber A and evaporator E flowing from gas pump F through conduits 55, 67 and 63 into vessel 64 then back to the gas pump F through conduits 68 and 54. The rich aqua flows by gravity from vessel 64 back into the upper portion of the analyzer 51.

From the foregoing, it will be appreciated that we have devised a new and novel refrigeration system having many advantages over systems heretofore known. Not only is the pressure equalizing medium forcibly circulated, but the pressure differential created for this purpose is also utilized to circulate the absorption medium between the boiler, absorber and analyzer in a novel and heretofore unknown manner. Moreover, by reason of our construction, the flow of inert gas and of absorption fluid may be so proportioned relative to one another by a proper design of the various vessels that the system operates at a maximum efficiency over a wide range of conditions without resort to the use of control or restricting devices within the system.

Furthermore, it will be obvious that our system lends itself to automatic control by the simple expedient of starting and stopping the gas pump F. If it is desired to vary the capacity of the apparatus, it is only necessary to vary the speed of the fan and the heat supply to the boiler. Varying the speed of the motor automatically varies the rate of gas circulation and of absorption solution circulation and in the proper relative ratios to one another as will be apparent from the foregoing.

We also wish to point out that either a single

or a twin gas lift pump may be employed to circulate the absorbent medium. If a twin gas lift pump is used, the solution may be equitably divided into two streams and delivered to separate vessels, as for example, the separate absorber vessels A' and A". As will be apparent from Figures 1 and 2, this pump may be located either at the inlet or at the outlet end of the absorber assembly.

5 10 15 20 25 30 35 40 45 50 55 60 65 70 While only two embodiments of the invention have been shown and described herein, it is to be understood that various changes may be made in the arrangement and construction of parts without departing from the spirit of the invention or the scope of the annexed claims.

We claim:

1. In an absorption refrigerating system, a boiler, an absorber having a plurality of sections, conduits for conveying liquid by gravity from the absorber to the boiler and an arrangement for delivering absorption liquid from the boiler to the absorber and for dividing the same into two streams, said arrangement including a twin lift gas-operated pump, and means for supplying gas thereto.

2. In an absorption refrigerating system, a boiler, an absorber, a conduit for conveying liquid from the absorber to the boiler by gravity and means for lifting the liquid from the boiler to a higher level for flow into the absorber, said means including a twin gas lift pump and means for supplying gas thereto.

3. In an absorption refrigerating system, an absorber having a plurality of chambers, means for supplying liquid to said chambers from a level below the same, and for dividing the liquid between said chambers, said means including a multiple discharge gas-operated pump and means for supplying gas thereto.

4. The combination, in an absorption refrigeration system of the type employing a refrigerant, an absorbent therefor, and a dense inert gas, of an evaporator, a boiler having an analyzer, and an absorber positioned above said analyzer, means providing a liquid circuit between said absorber, analyzer and boiler, and means providing a gas circuit between the evaporator and absorber, a power driven fan in said gas circuit, and a connection between said gas circuit and said liquid circuit whereby a portion only of said gas is utilized to lift the liquid to the top of the absorber from whence it flows by gravity through the remainder of the circuit.

5. In combination, an absorber for use in an absorption refrigeration system, means providing a circuit for the circulation of an absorbent liquid through the absorber, and power driven means for circulating a refrigerant-carrying dense, inert gas through the absorber, said last mentioned means including means for by-passing some of said dense gas to said liquid circuit to lift the liquid from a point below the top of the absorber to the top thereof whereby the absorbent flows by gravity through the remainder of the circuit.

6. The method of bringing an absorbent liquid into absorbing relation with a dense inert gas conveying a refrigerant medium in gaseous phase, comprising forming a column of said absorbent, forming a propelled stream of said gaseous mixture by creating a pressure differential therein, and bubbling a part only of said gaseous stream under a pressure in a high pressure area of said gaseous stream into said absorbent column to lift said column to an elevated position, and then

spreading out said absorbent into a gravity actuated stream presenting an extended surface area to the gaseous stream whereby said refrigerant is absorbed thereby.

7. The method of bringing an absorbent liquid into absorbing relation with a dense inert gas conveying a refrigerant in gaseous phase, comprising forming a column of said absorbent, forming a propelled stream of said gaseous mixture by creating a pressure differential therein, bubbling a part of said gaseous stream under pressure in a high pressure area of said gaseous stream into said absorbent column to lift said column to an elevated position and then bringing the absorbent stream in counterflow to but in intimate contact with the remaining part of the gaseous mixture stream whereby the refrigerant is absorbed.

8. In an absorption refrigeration system of the type using a refrigerant, an absorbent therefor, and a dense inert gas, the combination of a boiler, an analyzer communicating therewith, an absorber having at least a portion thereof above said analyzer, an evaporator means providing an inert gas circuit between said evaporator and said absorber, an absorbent circuit leading from said boiler to the top portion of the absorber and from the bottom portion of the absorber to the analyzer, power actuated circulating means in said gas circuit, and means for by-passing part of said gas from the discharge side of said circulating means and delivering the same to said absorbent circuit to lift the liquid to the top of the absorber from whence it flows by gravity back to the analyzer.

9. Absorption refrigeration apparatus of the type employing a refrigerant, a solvent therefor, and an inert gas, said apparatus comprising a refrigerant generator, a condenser, an evaporator, and an absorber interconnected to provide a refrigerant circuit, an inert gas circuit, and a solvent circuit, means operable independently of said evaporator to forcibly circulate the inert gas in its circuit, and means for by-passing some of the circulating gas into said solvent circuit to circulate the solvent.

10. Absorption refrigeration apparatus including a boiler, an absorber and an evaporator, means including the absorber and the evaporator for providing an inert gas circuit therebetween, means including the absorber and the boiler for providing an absorption fluid circuit therebetween, and common means operable independently of said evaporator for circulating the gas and the absorption fluid including means for by-passing some of the inert gas from its circuit into the absorption fluid circuit.

11. An absorber-boiler-analyzer assembly for a continuous absorption refrigeration apparatus comprising a boiler, an analyzer arranged at an angle to the horizontal and connected to the boiler, an absorber, absorption fluid conduits connecting the boiler, absorber and analyzer in circuit and arranged to provide gravity flow of absorption liquid from the boiler to the absorber, and means for circulating the absorption fluid through said circuit including a gas lift pump actuated by a gas which is non-condensable at ambient temperature.

12. That improvement in the art of refrigeration by means of a continuous absorption system of the type employing a refrigerant medium, an absorbent therefor, and a dense inert gas which includes positively circulating weak absorption fluid into intimate absorbing relation with a stream of refrigerant laden inert gas whereby

the refrigerant is absorbed, returning the enriched absorbent to a high temperature zone by gravity whereby refrigerant is liberated, and returning weak absorbent from said high temperature zone to said absorption zone by passing a part only of said gas stream into a column of the weak fluid.

13. A boiler-absorber assembly for an absorption refrigerating system comprising a boiler, an analyzer, an absorber and an absorption solution reservoir interconnected in circuit, said circuit including a twin gas lift pump operable to circulate absorption solution through the assembly and connected to elevate liquid from the boiler to the absorber, said reservoir being positioned intermediate the upper and lower extremities of said pump and connected to provide for the gravity return of enriched absorption solution to said analyzer.

14. An air cooled absorption refrigeration apparatus having an air-cooled condenser and an air cooled absorber of the inclined tube type in which the absorption solution flows downwardly therethrough in counterflow to the refrigerant gas being absorbed, said apparatus having a power driven fan for supplying a non-condensable gas under pressure to a gas lift pump in the absorption solution circuit discharging into the upper portion of said air cooled, inclined tubular absorber, said power driven fan being so constructed and arranged that only sufficient gas is delivered to the gas lift pump to circulate the absorption solution at the desired rate for efficient operation of said absorber.

15. An air cooled absorption refrigeration apparatus having a boiler-analyzer assembly, and an absorber connected in circuit therewith, said circuit including a solution reservoir and a gas lift pump device, said reservoir and pump being so positioned that a desired liquid level is maintained in said pump, said circuit also including a gas separation chamber into which said pump discharges and located above the lower portion of the absorber whereby the weak absorption solution flows from the boiler-analyzer assembly to the absorber and reservoir by gravity, and is thereafter elevated by the gas lift pump to the gas separation chamber from which it returns to said analyzer by gravity.

16. That improvement in the art of refrigeration by means of an absorption system having an absorption solution circuit and of the type charged with a refrigerant, an absorbent medium therefor and an inert pressure equalizing medium which improvement comprises forcibly circulating the pressure equalizing medium through an absorption zone and an evaporation zone, and by-passing a portion thereof into a circuit containing the absorption solution to circulate the same simultaneously with the pressure equalizing medium.

17. That method of circulating the absorption solution in a refrigeration system of the type containing a refrigerant, an absorbent medium therefor, and an inert pressure equalizing medium and of the type having a pressure equalizing medium circuit and an absorbent medium circuit, which method comprises forcibly circulating a principal stream of the inert pressure equalizing medium in its circuit, and diverting a portion thereof and bubbling it into absorption liquid in the absorption medium circuit to circulate the solution at a desired rate with respect to the principal stream of pressure equalizing medium.

18. That improvement in the art of refrigeration

tion by means of a system having a boiler, an absorber, conduits connecting the same in circuit, an inert gas circuit including said absorber therein, said system being chargeable with a refrigerant, an absorbent medium therefor, and an inert pressure equalizing medium, said improvement comprising raising the pressure of a portion of said inert medium and conducting separate portions thereof under pressure into two interconnected columns of absorption medium in the absorption medium circuit to divide a stream of absorption medium flowing to said columns into a plurality of streams.

19. A boiler-absorber assembly for an absorption refrigerator comprising a boiler having an analyzer, an absorber constructed and arranged for gravity flow of absorption liquid therethrough, conduits connecting said boiler, analyzer and absorber in circuit, said conduits including a gas lift pump located in a portion thereof normally containing absorption liquid, and means for circulating a main stream of inert non-condensing gas through the absorber, and means for diverting a portion only of said gas and introducing the same below the liquid level in said pump to circulate the absorption liquid at the desired rate for the efficient operation of said boiler-analyzer assembly.

20. A boiler-absorber assembly for an absorption system comprising a boiler, an analyzer therefor, an absorber and a solution reservoir interconnected in circuit, said circuit including a twin gas lift pump, said reservoir being positioned intermediate the upper and lower extremities of said pump, and means for introducing a non-condensable gas into said pump below the static liquid level therein to circulate absorption liquid in said boiler-absorber assembly.

21. Absorption refrigeration apparatus of the type employing a refrigerant, a solvent therefor, and an inert gas, said apparatus comprising a refrigerant generator, a condenser, an evaporator, and an absorber interconnected to provide a refrigerant circuit, an inert gas circuit, and a solvent circuit, means operable to create a substantial pressure differential in the inert gas circuit to circulate the gas therethrough, and means for by-passing some of the circulating gas at a raised pressure into said solvent circuit to circulate the solvent in its circuit.

22. Absorption refrigeration apparatus including a boiler, an absorber and an evaporator, means providing an inert gas circuit between the evaporator and absorber, means providing an absorption fluid circuit between the boiler and the absorber, and common means for raising the pressure of the inert gas in its circuit for circulating the gas in its circuit and for circulating the absorption fluid in its circuit, said common means including means for by-passing some of the inert gas from its circuit and at the raised pressure existing therein and bubbling it into the absorption fluid circuit.

23. An absorption refrigeration apparatus including a boiler assembly, a tubular air-cooled absorber arranged for gravity flow of absorption liquid therethrough, said absorber being arranged below the upper portion of said boiler assembly and connected to said boiler for the gravity flow of weak absorption solution thereto from the boiler, and power driven means for introducing a dense gas into a body of enriched absorption liquid obtained from the lower end of said absorber and elevating the same to a point from

which it may flow by gravity to the boiler assembly.

24. In combination, an absorption refrigeration system including a boiler assembly, an absorber having its upper end located below an upper portion of said boiler assembly, an evaporator, conduits interconnecting said evaporator and said absorber for the circulation of an inert medium therebetween, conduits interconnecting said boiler assembly and said absorber for the circulation of absorption medium therebetween the arrangement being such that weakened absorption solution flows to and through said absorber by gravity, means for circulating the inert medium in its circuit under pressure, means connected in parallel with a portion of said inert medium circuit and communicating with a high and a low pressure area therein, said parallel connection having a portion in common with said absorption solution circuit and constructed and arranged to bubble inert medium into the absorption solution to elevate the solution to a point from which it returns to the boiler assembly by gravity flow.

25. In combination, an absorption refrigeration system including a boiler, an analyzer communicating therewith, a tubular, air-cooled, inclined absorber assembly connected in a closed absorption solution circuit with said boiler and said analyzer and so positioned with respect thereto that weakened absorption solution flows by gravity to the upper portion of the absorber, an evaporator, conduits interconnecting said evaporator and absorber and providing an inert medium circuit therebetween, means providing a local circuit including a portion of the inert medium circuit and a portion of the absorption solution circuit, means for creating a pressure differential in the inert medium in that portion of the inert medium circuit included in said last-mentioned local circuit, the arrangement being such that said pressure differential causes inert medium to be bubbled into enriched absorption solution to circulate the same between the boiler, analyzer and absorber.

26. In combination, an absorption refrigeration system including a boiler, an evaporator, an absorber, conduits interconnecting said evaporator and absorber to provide an inert medium circuit therebetween, conduits interconnecting said boiler and absorber to provide an absorption solution therebetween, means for creating a pressure differential in said inert medium circuit to circulate a major portion of the inert medium therein, means connected in parallel with a portion of said inert medium circuit between points of differing inert medium pressures, said means having a portion in common with a part of said absorption solution circuit and being arranged to introduce inert medium into said solution.

27. In combination, an absorption refrigeration system including a boiler, an absorber having a plurality of branches, an evaporator, conduits providing a closed inert medium circuit including said evaporator and said absorber branches, means for creating a pressure differential in said circuit to circulate the inert medium therethrough, means interconnecting said boiler and said absorber branches to provide an absorption solution circuit therebetween, and means forming a part of said absorption solution circuit and utilizing inert medium withdrawn from a high pressure area in said inert medium circuit to divide absorption solution between said absorber branches.

28. In combination, an absorption refrigeration system including a boiler, an evaporator, an absorber having a plurality of parts, conduits interconnecting said evaporator and said absorber to provide an inert gas circuit therebetween and having portions interconnecting said absorber parts in parallel, conduits providing a circuit for absorption solution between said boiler and said absorber parts including portions interconnecting said absorber parts in parallel, means for creating a pressure differential in said inert gas circuit to circulate the gas therethrough, and means interconnecting said inert gas circuit and said solution circuit and utilizing said pressure differential to promote the circulation of the absorption solution in the solution circuit.

29. An absorption refrigeration apparatus including a generator, a condenser, an evaporator and an absorber connected in circuit, a gas impeller for circulating inert gas between the absorber and the evaporator, a gas lift pump for circulating absorption liquid between the absorber and the generator, means for supply inert gas from the discharge side of said gas impeller to the gas lift pump to actuate the same, and means for raising the static level of the liquid in said gas lift pump when the apparatus is operating above the static level of the liquid in the pump when the apparatus is not operating.

30. An absorption refrigeration apparatus including a refrigerant generator, an evaporator, and an absorber, an inert gas circuit connecting the evaporator and the absorber, an absorption solution circuit connecting the generator and the absorber, a gas impeller for circulating the inert gas in its circuit, a gas lift pump for circulating the absorption solution in its circuit, means for supplying inert gas from said inert gas circuit to said gas lift pump to actuate the same, and means connected between said inert gas circuit and said absorption solution circuit for depressing the liquid level in one part of said absorption solution circuit to raise the static liquid level in said pump.

31. In a fluid system having a plurality of gas and liquid circuits, the combination of a plurality of vessels through which the gas and liquid travel in contact, means for circulating a gas under pressure through said vessels, a plurality of liquid elevating conduits connected to said vessels, common means for supplying liquid to the lower ends of said conduits, and common means for directing at least a portion of the gas circulated through said vessels into said elevating columns below the liquid level therein.

32. In a fluid system having a plurality of gas and liquid circuits, the combination of a plurality of vessels through which the gas and liquid travel in contact, means for circulating a gas under

5 pressure through said vessels, a plurality of liquid elevating conduits connected to said vessels, common means for supplying liquid to the lower ends of said conduits, and common means for directing at least a portion of the gas circulated through said vessels into said elevating columns below the liquid level therein, the arrangement being such that gas discharged through said elevating conduits into said vessels immediately joins 10 the main stream of gas exiting from said vessels.

33. In a continuous absorption refrigerating system having a plurality of interconnected parts in open communication, an arrangement for lifting liquid from one level to another therein, said arrangement including an unobstructed U-tube, means for supplying liquid to the bottom of said U-tube, means for building up a gas pressure in 15 one part of said system and means providing unobstructed communication between said part of the system containing gas at said higher pressure and both legs of said U-tube, the arrangement being such that liquid is alternately discharged from the upper end of one of the legs of said U-tube and then from the upper end of the other leg of the U-tube.

34. A fluid system including means for placing a gas under pressure, a pumping structure including a plurality of unobstructed pumping passageways and a connecting passageway in 20 open communication with each of said pumping passageways, a source of liquid to be pumped, means providing open communication between said source of liquid to be pumped and said pumping structure, and means providing open communication between said gas under pressure and each of said pumping passageways adjacent the communicating portion thereof.

35. In an absorption refrigerating system using 25 inert gas, a pair of liquid receiving sections, a combined gas circulator and liquid circulator comprising a power operated gas pump, a twin gas lift liquid pump connected to discharge into said sections, and means for conducting gas from said gas pump to said twin gas lift pump.

36. In an absorption refrigerating system using 30 inert gas, a pair of liquid receiving sections, a combined gas circulator and liquid circulator comprising a power operated gas pump, a twin gas lift liquid pump connected to discharge into said sections, means for conducting gas from said gas pump to said twin gas lift pump, said twin lift liquid pump consisting of an unobstructed U-tube having means for supplying liquid to the bottom thereof, the arrangement being such that 35 liquid is discharged from the legs of said U-tube alternately.
